ILLINOIS

METHOD AND APPARATUS FOR FORMING HOLLOW METALLIC STRUCTURES

Application filed January 3, 1928. Serial No. 244,335.

The present invention relates broadly to the art of bending and shaping materials, and more particularly to the bending and shaping of metal sections in such manner that a plurality of such sections may be assembled to form a tubular structure.

One of the objects of the present invention is to provide a method and apparatus effective for rapidly and accurately forming up plate sections in such manner as to permit the assembly of successive sections by an interlocking operation, the invention not only insuring greater accuracy, but also giving greater rigidity in the formed articles with the same general mechanical appearance, and enabling the same to be turned out at a lower total cost than has heretofore been customary with the usual methods of construction.

With the above object in view, there is provided a method and means for accurately, expeditiously, and inexpensively assembling a hollow metal structure, of almost any desired total length, from ring sections, which sections are in turn formed up individually and rapidly from plate stock of such dimensions as will give the lowest materials cost.

In the accompanying drawings I have shown for purposes of illustration only one preferred apparatus adapted to facilitate the formation and fabrication of ring sections of the character referred to according to the method of my invention.

In the drawings, Figure 1 is a longitudinal vertical sectional view through one form of machine in accordance with the present invention.

Figure 2 is an end elevation, partly broken away, of the apparatus illustrated in Figure 1.

Figure 3 is a side elevational view of a typical fabricated product, and

Figure 4 is a detail cross sectional view of a typical form of ribbed joint produced in accordance with the present invention.

Figure 5 is a perspective view of a detail. In accordance with the present invention there may be provided an apparatus including a somewhat expansible hollow drum or C-shaped ring 1, in which the seam has purposely been left open to permit a limited ex-

pansion and retraction of the drum as may be required. This drum, as clearly indicated in Figure 1, has a tapered and threaded interior bore with which cooperates a bushing 2 having its outer periphery similarly tapered and threaded in such manner that it may be screwed into or unscrewed from the drum 1. This bushing has a substantially cylindrical interior bore provided with a thread having the same pitch and extending in the same direction as the thread on its outer surface, and cooperating with the threaded exterior of an inner spider or wheel 3.

The spider 3 is in turn carried by a longitudinally extending shaft 4 in such manner that it may be keyed thereto for rotation simultaneously with the shaft, or released therefrom to permit rotation of the shaft with the spider in predetermined fixed position.

For effecting engagement and disengagement between the shaft and the spider 3 there is provided a clutch 5 of the key type, adapted to be controlled at will by the machine operator through means of a double throw shifting mechanism, or equivalent device, 6, indicated at the left hand end of the machine in Figure 1. The key clutch 5 has a pivotal mounting 7 within the shaft 4 and comprises three fingers or arms projecting in a generally radial direction from the pivotal mounting.

In the position illustrated in Figure 1 of the drawings, the finger 8 of the key clutch 5 is in engagement with the spider 3, thereby insuring concomitant rotation of the shaft and the spider. By rotation of the hand wheel 6, the rod 9 may be moved to the left, thereby swinging the key clutch 5 in a counter-clockwise direction about its pivotal mounting, and effecting disengagement between the finger 8 and the spider. Continued rotation of the hand wheel in the same direction with the consequent shifting of the rod 9, will cause the finger 10 to assume a position such that when a key-way in a ring gear 11, mounted on the shaft 4 as shown in Figure 1, comes into alignment with the finger 10, one of the springs 12 will further

swing the key clutch in a counter-clockwise direction to effect engagement between the finger 10 and such key-way, whereby the gear 11 will be keyed to the shaft 4 for rotation therewith.

The gear 11 in turn meshes with a gear 13 carried by a shaft 14 extending transversely of the spider 3, and provided on its opposite end with a pinion 15 in mesh 10 with a gear 16 on a second shaft 17 also mounted in the spider, and carrying on its opposite end an elongated pinion 18.

The teeth of the pinion 18 mesh with the internal gear teeth 19 on the inner periphery 15 of the bushing 2, the bushing in this respect constituting a ring gear. Thus when it is desired to rotate the bushing 2, the hand wheel 6 is turned to move the rod 9 to the left, as viewed in Figure 1, this motion causing the key clutch to engage the gear 11 and in turn, through the various gears referred to, the bushing itself.

Upon rotation of the hand wheel 6 in the opposite direction, the key clutch 5 is turned 25 in a clockwise direction, as viewed in Figure 1, thus bringing it into such a position that when a key-way in the spider 3 comes into alignment therewith, the other of springs 12 will produce the desired engagement between 30 the key clutch and the spider.

The shaft 4 is carried in an elongated bearing 19 carried by a base 20 along which both the bearing and the shaft can be slid axially. Such movement of the parts is produced by a lead screw 21, which in turn may be driven by a motor 22 through a suitable gear train 23 controlled by a gear shift 24. With this gear shift in its dotted line position, as indicated in Figure 1, the 25 motor is operatively connected to the lead screw through the gear train. With the gear shift in its full line position, the motor is operatively connected through a second gear train 25 with the shaft 4 for rotating the 40 same. The construction of the parts is preferably such that different gear ratios are provided for driving the shaft 4 at different speeds, and the motor itself is also preferably of variable speed type for giving a further range of speeds to the operation of the 45 shaft.

The operative connection between the bearing 19 and the lead screw is provided by a projection 26 internally threaded to receive the lead screw, so that upon rotation 55 of this screw the bearing will be slid axially in one direction or the other.

The purpose of sliding the bearing 19 together with the shaft 4 is for enabling the 60 outer drum 1 indirectly carried by the shaft to be withdrawn axially from the rest of the apparatus when necessary for the proper operation thereof. This other apparatus comprises a pair of clamps 27, as shown in Figure 65 2, having a pivotal mounting 28 adjacent

their lower ends. Carried by one of the clamps is a motor bracket 29 on which is mounted a motor 30, the armature shaft of which drives a worm or spiral 31 meshing with a worm wheel or spiral 32. The gear 32 is carried by a shaft 33 supported in bearings 34 screwed to the clamp 27 which carries the motor bracket 29.

The other clamp 27 has, adjacent its free end, a pivot pin 35 extending transversely through the same and cooperating at its opposite ends with links 36. These links are in turn connected to a crank arm 37 driven by the gear 32. Consequently, by operation of the motor 30, it is possible to rotate the gear 32 and thus move the crank 37. Movement of this crank through substantially 180° in a counter-clockwise direction, as viewed in Figure 2, will loosen the clamps from the position shown in this figure, while rotation through a similar distance in the opposite direction will bring them into the position illustrated.

The clamps 27 adjacent their upper ends carry heavy electromagnets 38, while one or more similar sets 39 are provided adjacent their lower ends closely adjacent the pivotal mounting 28. All of these electromagnets are preferably so interconnected that they may be excited at will by means of a double throw switch 40 and the customary direct current supply lines 41, as indicated in Figure 1.

The clamps 27 are provided on their inner surfaces adjacent their opposite sides with any desired number of grooves 42, as indicated in Figure 1. Mounted for cooperation with a selected pair of these grooves are sets of spinning rollers 43, these sets of rollers being in spaced relationship axially of the shaft 4 with the rollers of each set circumferentially spaced. The rollers are preferably mounted on lever arms 44 and 45, having pivotal mountings 46 adjacent the periphery of the disks 47. These disks are threaded on the shaft 4 for rotation therewith, or axial movement therealong, as clearly shown in Figure 1. The keys 23' may be removed for axial adjustment of the disks on the shaft. The inwardly projecting ends of the levers 44 are provided with rollers 49, while the inner ends of the levers 45 carry similar rollers 50. The rollers 49 cooperate with a groove 51 in a nut 52, while the rollers 50 co-operate with a similar groove 53 in a nut 54. These nuts are both internally threaded for cooperation with the respective threaded portions provided on the shaft 4 on opposite sides of the spider 3.

Projecting laterally from the spider 3 is a rotation stop 55 adapted to control the operation of the nut 52. The rotation of the nut 54 may conveniently be controlled by a suitable brake 56 or similarly functioning device operated by an eccentric clamp, bolt, or other control mechanism 57 at the will of the oper-

ator, so that the nut 54 can be held at will against rotation at any desired time, while the shaft 4 rotates within it.

Although a single spinning roller might be used adjacent each side of the apparatus, there are preferably a plurality spaced equidistantly around the axis of the shaft 4 in such manner as to approximately balance the radial thrusts which would otherwise be encountered and which the shaft would have to withstand if only single rollers were utilized. Since each of the nuts 52 and 54 is adapted to simultaneously control a plurality of such rollers, increasing the number thereof does not involve any increased difficulties.

In Figure 1 of the drawings I have indicated a plate 58 in operative position within the machine with its opposite edges overlying certain of the grooves 42 in position to be engaged by the rollers 43. The groove or grooves 42 adjacent one side of the clamps 27 are just enough different as to dimensions from the grooves 42 adjacent the opposite sides of the clamps as to produce the formation in opposite edges of a plate of ribs of such character that if the rib formed in one could be put inside of that formed in the other, the two would be found to fit as accurately and completely as the difficulties of machine construction will readily permit. It will readily be apparent to those skilled in the art that the grooves may be arranged in any desired manner and so spaced, that different combinations can be utilized with plates of different widths, and that the supporting disks 47 and 48 can be so positioned as to cooperate with the desired arrangement of grooves.

This adjustment of the disks 47 can be effected by removing the keys which fasten these disks in position on the shaft, rotating said disks on the threaded portion of shaft on which such disks run like nuts, and then re-keying when the disks have reached the proper position axially along the shaft, to align with the required grooves.

The clamps 27 are also provided at suitable positions in their inner faces with other grooves 59 adapted to provide clearance room for one or more grips 60, as indicated in Figure 2. These grips are utilized for engaging the end of a plate 58 for drawing it around the drum 1 as the drum is rotated by the motor 22. These grips are conveniently mounted on a shaft 61 located just within the outer periphery of the drum so that they can be released and allowed to drop in radially to clear a plate 58 after they have performed their normal function.

Any type of mechanism which will accomplish this release and disappearance of the grips, under the control of the operator, can be utilized at will, the construction illustrated comprising eccentrically operated grips adapted to close when the control lever 62 is

moved in one direction, and release and drop inwardly when it is moved in the opposite direction. Any other preferred arrangement of grips might, however, be utilized at will.

As indicated more particularly in Figures 1 and 5, the machine may also be provided with control means 63 which comprising a hand operated cam shaft is adapted to throw a bolt in a generally radial direction in such manner as to engage with a suitable opening in the drum 1 to hold it stationary at such times as required when there is no plate 58 in position therein.

When such a plate is in position, the drum can still be readily held from rotation when required by energizing the various electro-magnets which can be so arranged and of such construction that the drum is firmly held even through the full thickness of the plate 58. Even after the drum has been released, its own great inertia can be utilized to prevent its material rotation until the bushing 2 has been driven backwardly to the extent required to properly collapse the drum.

In the preferred embodiment of the invention, the final seam between the two more or less parallel and straight edges of the plate 58, after the latter has been formed up, will be in proper operative relation to welding means 64 to permit such edges to be rapidly and accurately welded or otherwise joined together.

In order to facilitate a better understanding of the invention, there is illustrated in Figure 3 of the drawings one form of article adapted to be made in accordance with the present invention. In this figure there are indicated sections S and S' formed from plates such as the plate 58 adapted to be assembled with a third section S² under process of formation from another similar plate. Similarly, for purposes of description, and not as part of the invention itself, there is indicated a dished and flanged tank end 65 cooperating with the section S and a second similar head 66 similar to the head 65 except that its outer flange will be slightly different in radius, making it suitable for cooperation with the left hand rib, as indicated on the section S².

The heads 65 and 66 are only to be used when and if called for by the specifications of the particular structure being fabricated. Occasionally substantially flat tank ends are specified, and in Figure 1 I have indicated in dotted outline such a head, this again being for supplementary purposes and in order to indicate the adaptability of the machine in meeting the requirements of the various types of assembly.

In Figure 4 of the drawings there is indicated in section the type of joint produced for example between the section S and the section S'. It will be understood that this joint is similar to and representative of the vari-

ous other joints between the parts of any complete article.

In the normal use of an apparatus as herein described, there will be provided at one side of the machine, at proper height for ready feeding, a plurality of plates similar to the plate 58, each properly trimmed and ready for insertion into the machine.

Assuming that a preceding assembly process has involved the operation of the lead screw 21 for withdrawing the drum 1, spider 3, shaft 4 and bearing 19 to a point outside of the enclosing limits of the clamps 27, the first step in the new assembly operation will be the reversal of the motor 22 in order to restore the drum 1 and its associated parts to the position illustrated in Figure 1 of the drawings. Thereafter, the bolt operated by the control lever 63 is thrown to engage the proper opening, depression or slot in the drum 1 to thus hold the drum against rotation.

The gear shift 24 is then thrown to its full line position as indicated in Figure 1 and the gearing 25 set for low speed operation. The key clutch 5 being in position to engage the gear 11, the motor 22 is again started without further change in its direction of rotation and is thus effective for rotating the bushing 2 and to effect movement thereof to the right, as viewed in Figure 1, thus drawing the bushing into the drum and expanding the latter to its outermost position as determined in any desired manner, after which the motor is deenergized.

The control 63 is now thrown over to its release position to release the drum 1 and lie below the surface of the clamp 27 through which it projects. A new plate is then passed from the supply and the grips 60, shown in Figure 2, in a position in substantially the same horizontal plane with the axis of the shaft 4, but which are in reality located at this time closely adjacent the point of entry of the new plate, are operated to cause gripping engagement with the leading end of such plate. Thereafter, the hand wheel 6 is operated to disengage the key clutch 5 from the gear 11 and bring it into engagement with the spider 3, and the motor 22 is once more started at its lowest, or at a relatively slow speed. The clamps 27 having been left open after the completion of the preceding assembly operation, the new plate is drawn into position around the drum 1 until its ends are brought into closely adjacent relationship, after which the motor 22 is deenergized and the grips 60 released and moved inwardly, in the manner previously described, so as to lie within the periphery of the drum 1. The motor 30 is now energized to effect rotation of the gear 32 and consequent movement of the links 36 in such manner as to draw the clamps 27 toward each other about the drum, thereby forcing the new plate into final close

approximation of a truly circular shape under the tremendous pressure exerted by the clamps.

The clamps having been brought to this position, the motor 30 is deenergized in any desired manner, either manually or by a suitably arranged limit switch, as well understood in the art.

If desired, the electromagnets 39 may be energized prior to the release of the grips 60 by throwing the switch 40 to the proper position, thereby obviating any possibility of slippage of the plate from its previously determined position during the bringing together of the clamps.

The clamps now being in the position illustrated in Figure 2, and the clutch 5 having been disengaged, the control mechanism 57 is operated to apply the brake 56, it being assumed that the rotation of the control means for the inner nut 52 has been previously so adjusted that it need not be disturbed.

The gearing 25 may now be set at one of its higher speed positions and the motor 22 again energized, thus rotating the shaft 4 and forcing the nuts 52 and 54 to travel along threaded portions of the shaft 4, carrying with them the respective rolls 49 and 50. This in turn effects movement of the levers 44 and 45 in such manner as to swing the spinning rollers 43 into their respective grooves 42 in the clamps 27. This operation may be continued until the nuts 52 and 54 are brought into engagement with suitable limit stops or into engagement with the sides of the disks 47 and 48, thus stopping their travel and causing the brakes 56 or other appropriate control mechanisms for the nuts to slip until such time as the operator judges that the spinning process is completed. Thereupon he reverses the driving means 22, preferably setting it at still a higher speed for this purpose, and maintains such speed until the nuts 52 and 54 have been caused to retrace their paths to their original positions, approximately as shown in Figure 1. If desired, a limit stop or limit indicator 67 may be provided for cooperation with the nut 54, although such a device is not essential. When the nuts have reached their proper positions, the motor 22 is again deenergized.

At this time the further procedure depends upon whether or not any left-hand end head 66 is to be incorporated in the completed assembly of parts. If such a head is to be incorporated, the entire rotor element, including drum 1, spider 3, and associated parts, are withdrawn by means of the lead screw 21, so as to entirely clear the position of the head to be inserted, regardless of its shape. If no such part is to be incorporated, however, it is only necessary to contract the diameter of the drum 1 sufficiently to en-

able it to clear the inner face of the formed ring, but it need not be removed from the position illustrated in Figure 1 in order to permit the final removal of the completed ring section and its incorporated parts.

In order to completely describe the operation of the machine, there will first be assumed a condition of operation in which a head of the character referred to is to be incorporated. In such case, when the nuts 52 and 54 have reached the left hand limits of their travel, as viewed in Figure 1, the motor 22 is shut off and the shaft 4 allowed to slow down until it is turning over slowly enough to permit the clutch 5 or the equivalent device provided for that purpose to be operated through the medium of the hand wheel 6 to bring it into such position as to engage the gear 11. At this time, the motor gear train 25, having again been set to a low speed position, the electromagnets 38 and 39 are energized by proper movement of the switch 40, and the motor 22 again brought into operation, with the clutch 5 in such position as to engage the gear 11 in order to back out the bushing 2 to an extent sufficient to permit contraction of the drum to a small enough diameter to permit its ready sidewise removal from the formed-up plate.

This sidewise removal is accomplished by deenergizing the motor 22 until such time as the gear shift 11 can be moved to its dotted line position and the gear train 25 again changed to its high speed point. At such time the motor 22 is again energized, preferably at its highest speed of rotation, so that the entire rotor element, including the drum 1 and its associated parts, is rapidly moved to the left, as viewed in Figure 1, at which time the motor is again shut down.

The electromagnets 38 and 39 are maintained energized and the driving means 30 operated to open the clamps 27 and with them, due to the action of the electromagnets, the now formed plate ring, ready to permit the entry of a previously formed ring section or the entry of a suitably shaped right or left hand head, or any other part as required by the specification.

After the proper positioning of such part or parts in their respective grooves provided, the motor 30 is energized to once more draw the clamps 27 into operative position to close the last formed plate ring about the part or parts previously positioned in the desired grooves 42. With the clamps in closed position, the motor 30 is deenergized, thus leaving the component parts of the final tubular structure, insofar as as they have been assembled by this operation, firmly locked together. In this position the axial seam between the two approximately parallel ends of the last formed plate ring may be closed permanently by means of the arc welder or welders 64, or by any other equivalent or de-

sired means for accomplishing the purpose intended, either directly or indirectly. For example, the plate ring might conceivably be held temporarily by a suitable mechanical clamp, by one or more rivets or bolts, or by a desired species of dovetailing previously incorporated in the ends of the plate, and the final sealing up or completion of the seam carried out as a subsequent step after the parts have left the machine.

With such welding or mechanical closure of the axial seam in the last formed plate ring, the process of assembly by a machine in accordance with the present invention ceases, it being now only necessary to again energize the motor 30 to open the clamps 27 and thus permit the removal of the formed up and assembled parts.

If the new ring section just formed constitutes an intermediate, and not an end section of the total tubular structure being fabricated, upon its withdrawal to one side of the machine it may correspond for example to the section S of Figure 3, where it is ready for the incorporation therewith of the next ring section S' to be subsequently formed up. In this manner, the parts are formed and assembled until a complete tubular structure is produced, of any desired number of sections or length, which may or may not be provided with one or both ends headed, at the user's option.

The carrying out of the process herein described leads to several important advantages besides those of rapid production and relatively low cost. Thus, the ribs pushed out or formed around the circular edges of the formed up ring plate are precisely and accurately positioned and placed, thereby leading to greater accuracy in the final structure regardless of whether the original raw plate was a perfect rectangle or more or less trapezoidal in its contour, and regardless of whether it was wavy, of non-standard width, or positioned slightly askew in the machine. These constitute important manufacturing advantages not only because of the production of more accurate articles regardless of errors in any preceding operations, but because of the fact that they obviate the necessity of that degree of accuracy in preceding operations with respect to trimming, shearing, and feeding of the parts as has before been necessary.

A structure produced in accordance with the present invention will be strong, and firmly held together mechanically without further processing. If, however, it is to be made liquid or gas tight, all of the seams may be hot-dip brazed, galvanized, electric arc or gas welded, or otherwise sealed in a subsequent operation, independent of the steps of assembly before referred to.

The projecting circular ribs as formed being machine constructed in accordance

with the present invention, not only serve as a logical, convenient and effective mechanical means for joining successive ring sections, but at the same time give that projection of the joint outwardly from the general cylindrical surface of the article necessary to permit ready entry into the molten brazing, galvanizing, or other bath, whereby a substantial inexpensive and expeditious method of sealing is obtained.

While I have herein illustrated and described a preferred embodiment of the present invention, it will be understood that changes in the construction, arrangement and operation of the parts may be made without departing either from the spirit of my invention or the scope of my broader claims.

It will also be apparent that changes in the contour of the various sections may be made at will. The expression "tubular" and similar terms used throughout the specification and claims are thus definitive of a wide variety of different shapes, it being only necessary within such terminology that the opposite end portions of a plate shall be brought into adjacent relationship.

I claim:

1. In a machine of the character described, means for bending a plate into the desired form, electro-magnetic means for holding the plate in formed position, means for forming a flanged projection near one edge of said plate, and means for moving said electro-magnetic means to open the formed plate and facilitate the assembly therewith of a second plate.

2. In a machine of the character described, means for bending a plate into the desired form with the end portions thereof in adjacent relationship, holding means for said plate, means for forming a flanged projection near one edge of said plate, and means for moving said holding means to separate the end portions of the plate and permit the assembly with said plate of a previously formed plate section.

3. In a machine of the character described, means for bending a plate into the desired form with the end portions thereof in adjacent relationship, holding means for said plate, means for forming a flanged projection near one edge of said plate, and means for moving said holding means to separate the end portions of the plate and permit the assembly with said plate of a previously formed plate section, said holding means comprising an electro-magnet.

4. In a machine of the character described, means for forming a plate to bring the end portions thereof into adjacent relationship, means for deflecting an edge portion of said plate, and means operable at will for opening or closing the formed plate to effect a separation of the end portions thereof.

5. In a machine of the character described,

means for forming a plate to bring the end portions thereof into adjacent relationship, means for deflecting an edge portion of said plate, means operable at will for opening or closing the formed plate to effect a separation of the end portions thereof, and means for securing said end portions one to the other.

6. In a machine of the character described, means for bending a plate to bring the end portions thereof into adjacent relationship, means for shaping the opposite edges of said plate to provide interlocking projections thereon, means for separating and bringing together said end portions at will, and means for securing said end portions.

7. In a machine of the character described, means for deflecting a plate into the desired form with the end portions thereof in adjacent relationship, means for producing an interlocking element near one edge of said plate, means for expanding the formed plate to permit the association with said interlocking element of an interlocking element on a previously formed plate, means for contracting said plate to interlock said elements, and means for joining the end portions of said plate.

8. In a machine for fabricating metal structures, means for forming interlocking ribs on shaped sections, means for joining the ends of the shaped sections, and means for expanding and contracting at will a shaped section prior to the joining of the ends thereof to facilitate the assembly therewith of another section.

9. In a machine of the character described, a drum, means for fitting a plate around said drum, means for expanding or contracting said drum, clamping means extending peripherally of said drum, means for operating said clamping means, and means for moving the drum and clamping means relatively one to the other in a direction axially of the drum.

10. In a machine of the character described, a drum, means for fitting a plate around said drum, means for expanding or contracting said drum, clamping means extending peripherally of said drum, means for operating said clamping means, means for moving the drum and clamping means relatively one to the other in a direction axially of the drum, and means cooperating with said drum and clamping means for forming an interlocking element on a plate in position therebetween.

11. In a machine of the character described, a drum, means for fitting a plate around said drum, means for expanding or contracting said drum, clamping means extending peripherally of said drum, means for operating said clamping means, means for moving the drum and clamping means relatively one to the other in a direction axially

- of the drum, and means cooperating with said drum and clamping means for forming interlocking elements on a plate in position therebetween.
12. In a machine of the character described, means for fabricating a shaped section having cooperating parts, means for interlocking said section with a second section previously formed, and drawing the cooperating parts of said first section into engaging relationship, and means for holding said sections in assembled relationship. 70
13. In a machine for fabricating metal structures, means for forming a succession of sections having interlocking elements formed thereon, means for successively expanding one of said sections to permit the assembly therewith of a previously formed section and thereafter contracting the expanded section, and means for securing said contracted section in contracted position, whereby said interlocking elements unite said sections. 75
14. In a machine for assembling tubular metal structures of indefinite length, rotating means for pulling a plate into substantially tubular form, co-acting exterior and interior means for holding such formed plate in substantially cylindrical shape, means for forming a bead at the end of the cylinder, 80
- means for opening up and then closing in a beaded end to permit interlocking assembly with a similarly and previously formed cylinder, and other means for finally securing together the meeting edges of said formed plate so as to permanently interlock with said previously formed cylinder. 85
15. In a machine for assembling interlocked tubular metal structures of indefinite length, means for pulling a plate around a rotating drum, exterior clamping means for forcing said plate into a substantially cylindrical shape, roller means for forming interlocking projecting ribs at an end of the cylinder, means for then holding the formed plate and opening it sufficiently to permit interlocking assembly with a substantially similar and previously formed plate, clamping means for effecting such assembly, and means for securing the meeting edges of the plate solidly together after such assembly. 90
16. In a method of assembling hollow cylindrical metal structures, the steps comprising pulling a plate around a rotating drum, then exteriorly clamping such plate solidly into substantially cylindrical form, rolling projecting ribs near the ends of the formed up cylinder, opening up the cylinder to permit entrance of a similar rib on a previously formed up plate, then closing down the last formed rib upon the previously formed one, and finally securing solidly together the meeting edges of the last formed plate so as to make the interlock permanent. 95
17. In a method of assembling hollow cylindrical metal structures, the steps comprising pulling a plate around a rotating drum, then exteriorly clamping such plate solidly into substantially cylindrical form, rolling projecting ribs near the ends of the formed up cylinder, opening up the cylinder to permit entrance of a similar rib on a previously formed up plate, then closing down the last formed rib upon the previously formed one, finally securing solidly together the meeting edges of the last formed plate so as to make the interlock permanent, and thereafter applying a metallic liquid tight seal to all exposed seams. 100
18. In a method of assembling long, hollow, metallic, multi-sectional structures, the steps comprising deflecting a plate into a substantially tubular form, rolling a continuous and projecting hollow interlock rib near one of the circular edges of the formed up plate, opening up such ribbed edge so as to permit assembly of the newly formed up plate with one previously formed, reclosing said opened up-rib so as to solidly grip the interlocking rib of a previously formed plate, and sealing all joints so as to make a fluid tight structure. 105
19. In a method of assembling indefinitely long hollow metallic multi-sectional structures, the steps including pulling a plate around a rotating drum, forming edge interlock elements on said plate, opening up one interlock element to permit the entrance of a co-acting interlock element on a previously formed similar tubular section, inserting such co-acting element, and reclosing the opened-up section. 110
20. In a method of assembling indefinitely long hollow metallic multi-sectional structures, the steps including pulling a plate around a rotating drum into tubular form, forming edge interlock elements on said plate, opening up an edge interlock element of the newly formed section so as to permit interlocking assembly with the interlock element on a previously formed section, reclosing the newly interlock element so as to form a mechanically firm joint around the previously formed element, and permanently connecting adjacent edges of said opened-up section. 115
21. In a method of assembling indefinitely long hollow metallic multi-sectional structures, the steps including pulling a plate around a rotating drum to form a tube, rolling edge interlock elements in the formed plate, opening up at least one of said interlock elements slightly so as to permit the interlocking entrance thereinto of a previously formed smaller interlock element, reclosing the opened-up interlock element tightly over the previously formed element, and firmly securing the axial edges of said opened-up plate so as to form a mechanically integral structure with the previously formed interlock element. 120
22. In an apparatus for assembling circular hollow multi-sectional metallic structures, a 125

rotatable collapsible drum for bending a plate into substantially tubular form, grooved means enclosing said drum, roller means cooperating with said grooved means for forming interlock elements in said plate, and means for collapsing said drum to permit the removal of the formed plate therefrom.

23. In a machine of the character described, a rotatable mandrel for progressively deflecting a metallic plate into substantially tubular form, contractible means having grooves for gripping the formed plate on said mandrel, and rotating means cooperating with said grooves to form hollow bead interlocking projections adjacent the ends of said formed plate, said hollow beads being similar in shape but of different dimensions.

24. In a machine of the character described, a rotating form for progressively deflecting a metallic plate into substantially tubular shape, means for contracting around said form to hold the plate thereon, said means having circumferential grooves, means cooperating with said grooves for forming parallel hollow interlock ribs near the circular edges of the formed plate, said hollow interlock ribs being similar in shape but of different dimensions, means for tightly closing an interlock rib on a newly formed plate over a similar rib on a previously formed plate, and means for securing together the ends of the newly formed plate.

25. In a machine for fabricating metal structures, means for bending a plate into substantially tubular shape, means cooperating with said bending means for holding a formed plate in position, rotating means cooperating with said holding means for forming interlock beads of similar shape but different dimensions close to the circular edges of the formed plate, means for slightly opening and reclosing the formed plate to receive in one of its interlock beads a matching bead in a previously formed similar plate, and means for securing together the ends of the last formed plate.

26. In a machine of the character described, a rotatable form for progressively bending a metal plate into substantially tubular shape to bring the end portions thereof into engagement, external and internal means for gripping said formed plate and forming interlock beads adjacent the circular edges thereof, means for slightly opening one of the beads and reclosing it firmly about a matching bead in a previously formed plate, and means for securing together the ends of the last formed plate.

27. In a machine of the character described, a form for receiving a metal plate bent to cylindrical shape, internal and external means cooperating with said form to produce interlock beads adjacent the circular edges of the plate, means for opening up and closing a newly formed hollow bead over

a matching bead on a previously formed plate, and means for securing together the ends of the last formed plate.

28. In a machine of the character described, cooperating internal and external means for producing interlock beads in the circular edges of a plate bent to tubular form, means for opening up the bent plate and reclosing it in interlocking engagement with a previously formed similar plate, means for tightly closing the ends of the last formed plate and means for securing said ends firmly together.

29. In a machine for fabricating tubular metal structures, means for holding a shaped tubular plate, means for producing edge interlocking beads in said plate while so held, means for opening up a formed plate and contracting it around a previously formed plate to effect engagement of the beads on adjacent plates, and means for permanently securing together the ends of the last formed plate.

30. In a method of fabricating tubular metal structures of a definite length, the steps including pulling a plate around a rotatable form to give it substantially cylindrical shape, forming interlocking ribs adjacent the circular edges of the formed plate, opening one of said ribs, inserting a corresponding rib of a previously formed plate, reclosing the opened-up rib, and firmly securing together the ends thereof.

In witness whereof, I hereunto subscribe my name.

JAMES LUCIAN ADAMS, JR.
